(57) **CLAIM**

I claim the ornamental design for a nested furniture module, as shown and described.

DESCRIPTION

FIG. 1 is a perspective view of a nested furniture module;

FIG. 2 is a perspective view thereof, depicted with an alternate configuration shown in broken lines;

FIG. 3 is a perspective view thereof, depicted with an alternate configuration shown in broken lines;

FIG. 4 is a perspective view thereof, depicted with an alternate configuration shown in broken lines;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The broken lines shown in the drawings form no part of the claimed design.
